REFRIGERATING SYSTEM

John Kirgan, Easton, Pa., assignor to Ingersoll-Rand Company, Jersey City, N. J., a corporation of New Jersey

Application June 17, 1936, Serial No. 85,653

7 Claims. (CL. 62—115)

My invention pertains to refrigerating systems, and especially to a refrigerating system designed to meet the requirements of all conditions of operation from maximum to minimum output.

5 It is a particular object of this invention to provide a refrigerating system wherein a liquid refrigerant is partially vaporized and chilled, and wherein the vapor so formed is condensed, the system being so constructed that it can be 5
10 advantageously operated over the entire load range. To this end the practical embodiment of the system comprises parts or members which can be connected and operated in several different ways to maintain the expenditure of power substantially in proportion to the amount of refrigerating effect that is needed.

Another object of the invention is to provide 20 condensing apparatus in such a refrigerating system wherein the consumption of the heat-absorbing medium, such as water, for liquefying the vapor formed in the process of partial vaporization, can be much reduced when the refrigerating load drops. Thus, in its preferred form, the system includes an evaporator for the refrigerant, 25 evacuators for removing the vapor from the evaporator and for delivering such vapor to the condensing apparatus, the condensing apparatus comprising several separate condensers which may be utilized in several different ways 30 to effect the desired economy of cooling medium consumption.

A still further object of the invention is to enable the relationship between the evaporator, the evacuators, and the condensers to be changed 35 as desired, to afford the greatest possible economy for part-load operation over a long period of time.

For removing vaporized refrigerant from an evaporator a centrifugal compressor has been 40 found to produce good results, because it is self-regulating in power consumption and to a great extent self-stabilizing in function. This is characteristic of such a machine at heavy loads and somewhat less, but at very light loads difficulties may arise, for as the load decreases the degree 45 of compression demanded of the compressor becomes greater and the operation of the compressor tends to become unsteady and at very light loads is manifested by surging of the vapor in the compressor. My system of refrigeration 50 is well adapted for use with a centrifugal compressor under light load conditions and comprises several such units connected to operate in variable relation to each other and at variable speeds according to the requirements of any condition that may be encountered.

I shall make clear other objects and advantages of the invention in the description of the form of the invention illustrated herein, but the right is reversed to change the structure of the apparatus and mode of procedure without departing from the principle or scope of the invention as set forth in the appended claims.

On the drawing Figure 1 shows in outline an arrangement of parts according to this invention, and

10 Figures 2 and 3 present details, Figure 3 being a section on line 3—3 of Figure 2.

The numeral 1 indicates a vessel enclosing an evaporator chamber having near the top thereof an inlet header 2 with spray openings through 15 which water or other liquid refrigerant issues in the form of jets into the chamber from a pipe 3. Some vaporization of the liquid occurs, but the greater portion of the refrigerant remains liquid and passes into the outlet conduit 4. In this 20 pipe the refrigerant is conducted to a cooling coil or other device. There the refrigerant absorbs heat and may thereafter return to the evaporator by way of the pipe 3.

The evaporator 1 has outlets 5 in the top leading 25 to the intakes of evacuators that both withdraw the vapor and maintain the proper vacuum in the chamber. The evacuators are centrifugal compressors in housings 6 and 7. The compressors raise the pressure of the vapor formed 30 in the chamber and force the vapor into condensers 8 and 9. The compressors are each rotated by a separate variable speed motor 10 through shafts and suitable step-up gearing 11. Each motor 10, if an electric motor, may be connected 35 by wires 31 to the supply wires 30, and in one of the wires 31 may be placed a variable resistance as diagrammatically illustrated at 32, for varying the speed of each motor. It will be understood, however, that other types of motors, 40 such as steam turbines, for example, may be utilized if desired.

The two condensers may be cooled by any suitable medium, such as water, supplied by a pipe 12 and carried away therefrom by a pipe 13. 45 These condensers have interior tubes through which the cooling medium flows while the vapor of the refrigerant is being liquefied by contact with same. After being condensed the vapor will be conducted from each condenser through the 50 pipes 14 back into the pipe 3 or evaporator 1. The condensers will of course be provided with suitable air removal pumps (not shown) for the purpose of maintaining the desired vacuum therein.

With this apparatus different adjustments can be made for operation under heavy and light load conditions. The two compressors can operate together at full speed, or one may be so operated and the other may be run at reduced speed or shut down entirely, or both compressors or one alone may run at a reduced speed. A great deal of flexibility is thus secured. Thus the mass and rate of removal of the vapor extracted by each compressor can be regulated as conditions demand.

Also under some circumstances the apparatus may be required to run for long periods of time at reduced load and at the same time use a minimum supply of cooling water for the condensers. In that case the outlet flue 15 of the evacuator 6 may be coupled to the inlet neck or flue 16 of the evacuator 7 through a cross connection 17, and this connection may have valves to break communication between the compressor 6 and its condenser 8 and put this compressor in series with the other compressor 7, which is then disconnected from the evaporator 1. The valves may be located at the junction of the cross connection with the pipes 15 and 16. Such a valve is shown at 18 having a spindle 19 at one end in suitable bearings where the flue 17 joins the flue 15. In one position this valve will close the flue 17 while leaving the flue 15 open, and in another position it will close the flue 15 and open the flue 17 so that the compressors are in series instead of in parallel. See Figure 2.

A similar valve element at the junction of the flue 17 and inlet neck 16 of the other compressor 35 may be used for the same purpose to shut the flue 17 when the compressor 7 is to work in parallel with the compressor 6, or to cut off the compressor 7 from the evaporator 1 and connect the flue 17 to the inlet side of this compressor. Thus 40 the one compressor 7 may be cut off from the evaporator 1 to receive the discharge of the other compressor 6, both compressors then delivering to one condenser 9 while communication is interrupted between the compressor 6 and condenser 8. When so related the two compressors 45 will most of the time be operated at reduced speed to save horsepower, but even at low speed in series arrangement they will produce a considerably higher ratio of compression than would either compressor operating at full speed. That 50 is to say, the vapor in the evaporator 1 is compressed to a greater extent by the two compressors in series before it reaches the condenser 9. Hence the inside pressure of the condenser 9 will 55 be higher and the water which circulates through the condenser to cool it can be used in smaller quantity.

To hold each valve 18 in either position, the spindle 19 has an arm 21 with a threaded bolt 22 passing through a threaded opening in its outer end. This bolt has a head 23 to serve as a knob or handle. This bolt can be screwed into threaded openings in projections 24 on the outside of the pipes 15, 16 and 17, there being two 55 projections at each junction at such points as will enable each valve to close one or the other pipe at the junction controlled by said valve.

While the two compressors may be operated in parallel as described above and deliver to separate condensers supplied with cooling water at the same temperature, or in series and deliver to a single condenser, another arrangement that can be adopted is to cause the cooling water to pass through the condensers in series when the two compressors are in parallel, that is, to connect

the discharge pipe 13 of the condenser 8 to the admission pipe 12 of the condenser 9. In this case one compressor must compress the vapor to a higher pressure than the other, because the pressure in the condenser 9 will be higher. The 5 compressor 7 is therefore operated on a different part of its capacity curve and will extract somewhat less vapor from the evaporator 1 than the other. Hence condenser water can be saved in this instance likewise.

The connections for the changes in the arrangement are shown in Figure 1 where a length of piping 25 unites the inlet 12 of the condenser 9 to the outlet 13 of the condenser 8. The pipe 12 of the condenser 9 has a shut-off valve indicated at 26, and the pipes 13 and 25 have similar shut-off valves 27 and 28 respectively. When the valve 28 is closed and the other two are open, the two condensers operate independently. When however, the valve 28 is open and the valves 20 in the pipes 12 and 13 are closed, then the two condensers are in series.

If the compressors are identical in design and size and run in parallel at the same speed, they now divide the single mass of vapor in the evaporator 1 into separate portions and compress these portions unequally. One portion is delivered by the compressor 6 to the condenser 8 and the remainder is delivered by the compressor 7 to the condenser 9. The cooling water in this condenser 9 will be somewhat higher in temperature than in the condenser 8. Hence the evacuator 7 will work against a slightly higher back pressure and will compress the vapor to a greater extent, although the suction pressure for each compressor is the same. The compressor 7 will therefore operate on a different part of its capacity curve, and will extract somewhat less vapor from the evaporator than the other compressor 6.

The water needed for the condensers may thus be diminished and operating costs cut down, while at the same time the necessary reduction in temperature of the water entering the evaporator is rendered possible. The system operates well at full load or part load. A centrifugal compressor in a refrigerating system of this type running at constant speed, is self-regulating, that is, the power for operating same is automatically reduced when the load is reduced. Also the operation of the compressor is quite 50 stable over a greater range than when it is utilized for other purposes. Generally a centrifugal compressor will run unsteadily and the vapor will surge when the load falls to about two-thirds of the full load. In a refrigerating system as set forth above, however, the compressor load remains stable until a much lighter load is reached. Therefore the two compressors running in parallel with the condensers in series will cooperate at full output of the system, though the compressor 60 7 then operates at less than its total capacity, and at part load also until the point where surging in one compressor will begin. So that surging of the vapor in either compressor will not interfere with normal operation, even at relatively low load, a suitable automatic governor or controlling device may be attached to each compressor when the condensers are in series, to take effect at the right moment; that for the compressor 7 to act first because this compressor may 65 attain instability of load before the other, or the compressor 7 may be stopped at a selected point by switching off its motor 10 while the other compressor continues to operate.

The centrifugal compressor is virtually self- 75

stabilizing in function because, as is well known with a drop in load, the water entering the evaporator is cooler, and the vapor formed is less in density but larger in specific volume. Also the pressures in the evaporator and in the condenser diminish, but the ratio of compression of the centrifugal compressor increases. The drop in pressure and density of the vapor with increase of volume and greater compression are the factors that tend to maintain the normal operation of the compressor until the load becomes small. Hence, as the demand for refrigeration lessens, while the rated speed of the compressor continues, the power consumed by the compressor is reduced, but no loss of stability ensues before very light load is reached.

When the compressors 6 and 7 run in parallel and the condensers 8 and 9 are connected in series, the compressors can be run together at full speed, or one at full speed and the other at reduced speed, or either can be run alone at full speed or less. When the compressor 7 operates alone or with the compressor 6 at any speed less than full speed of the latter, the water in the condenser 9 will not be warmed so much and therefore the temperature and pressure in the condenser 9 will be less, thereby permitting the compressor 7 to force the vapor into the condenser 9 more easily. The compressor 7 now will be more stable than when operating with the compressor 6 and the former runs at the full speed which can be imparted to it by its motor 10.

An additional valve 29 may be placed in the water inlet pipe 12 for the condenser 8, and any or all of the valves 26, 27, 28 and 29 may be automatically controlled in accordance with conditions in the system to control the cooling water for the condensers. Automatic regulation of the valves 18 may of course also be practiced, the valves then being arranged to operate in unison or separately in accordance with variations in load within the system. It will, of course, be clear that more than two compressors or condensers arranged in the manner shown, may be used if desired, two having been shown only for the purpose of illustration.

Thus it will be seen that the system may be operated in various ways and is readily adaptable to part load operation. The speed of the compressors may be varied and the rate of evacuation varied accordingly to partly compensate for load changes. The condensers and evacuators may be placed in various relations to each other and cooling water saved, or the relationship between the compressors may be altered to effect further savings in the cost of operation.

I claim:

1. In a refrigerating system, an evaporator chamber, a plurality of evacuators for removing vapor from the chamber, condensers to which the evacuators discharge, and means for eliminating the communication between some of the evacuators and the chamber and for placing such

evacuators in series with the other evacuators when the load on the refrigerating system drops.

2. In a refrigerating system, an evaporator, a plurality of evacuators for the evaporator, a separate condenser for each evacuator, connections for supplying cooling medium separately to each condenser, means for altering said connections to cause the cooling medium to pass serially through the condensers, means for selectively connecting each evacuator in series with the evaporator and its condenser or connecting the evacuators in series with each other and with the evaporator and one of said condensers, and means for varying the operating speed of one or more of said evacuators thereby varying the rate of evacuation of said evaporator.

3. In a refrigerating system, an evaporator, a plurality of evacuators for the evaporator, condensers to which the evacuators discharge, and means for varying the relationship between the evaporator, evacuators, and condensers to maintain the consumption of power in the system substantially proportionate to the load thereon, said means being positioned to arrange some of the evacuators selectively in parallel or in series with each other with respect to their connection to the evaporator.

4. In a refrigerating system, an evaporator, a plurality of vapor evacuators for the evaporator, a separate condenser for each evacuator, and means for selectively directing the flow of vapor from the evaporator in parallel streams through each evacuator into its condenser or directing such flow in one stream through the evacuators in series and into one of the condensers.

5. In a refrigerating system, an evaporator, a plurality of evacuators for the evaporator, a separate condenser for each evacuator, means for alternatively connecting the outlet of one evacuator to its condenser or to the inlet of a second evacuator, and means for alternatively connecting the inlet of said second evacuator to the evaporator or to the outlet of said one evacuator.

6. In a refrigerating system, an evaporator, a plurality of evacuators for the evaporator, a separate condenser for each evacuator, a conduit connection between the outlet of one evacuator and the inlet of a second evacuator, valve means at one end of the connection to alternatively connect the outlet of said one evacuator to its condenser or to said connection, and valve means at the other end of said connection to alternatively connect the inlet of said second evacuator to the evaporator or to said connection.

7. In a refrigerating system, an evaporator, a plurality of evacuators for the evaporator, separate means for each evacuator to condense vapor discharged therefrom, and means for selectively connecting the evacuators in series with each other and with the evaporator and one of said separate condensing means.

JOHN KIRGAN.
